(57) **CLAIM**

The ornamental design for a hexagonal cup, as shown and described.

DESCRIPTION

FIG. 1 is a perspective view of a first embodiment of a hexagonal cup showing our new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a bottom perspective view thereof; FIG. 9 is an environmental perspective view thereof; FIG. 10 is a perspective view of a second embodiment of a hexagonal cup; FIG. 11 is a front view thereof; FIG. 12 is a rear view thereof; FIG. 13 is a left side view thereof; FIG. 14 is a right side view thereof; FIG. 15 is a top view thereof; FIG. 16 is a bottom view thereof; FIG. 17 is a bottom perspective view thereof; and, FIG. 18 is an environmental perspective view thereof. The broken lines are environmental or otherwise depict portions of the hexagonal cup that form no part of the claimed design.
